TELESCOPIC CRANE BOOM

Stanley R. Spain, Greencastle, and Henry A. Kohler and
Eugene C. Gardenhour, Waynesboro, Pa., assignors to
Walter Kidde & Company, Inc., Clifton, N.J.

Filed May 8, 1973, Ser. No. 360,601

Term of patent 14 years

Int. Cl. D15—04

U.S. Cl. D12—54

FIG. 3

FIG. 4

FIG. 5

FIG. 6

FIG. 8

FIG. 9

FIG. 10

FIG. 7

FIG. 1 is a perspective view of a telescopic crane boom showing our new design, the view showing the front, bottom and one side thereof in retracted position;

FIG. 2 is a side elevational view, on a reduced scale, showing the opposite side thereof;

FIG. 3 is a top plan view thereof;

FIG. 4 is a bottom view thereof;

FIG. 5 is a front elevational view thereof on an enlarged scale;

FIG. 6 is a rear elevational view thereof on an enlarged scale;

FIG. 7 is a side elevational view, on a reduced scale, of the side thereof shown in FIG. 1 and showing the telescopic crane boom in extended position;

FIG. 8 is an enlarged view of fragmentary portion A of FIG. 7;

FIG. 9 is an enlarged view of fragmentary portion B of FIG. 7; and

FIG. 10 is an enlarged view of fragmentary portion C of FIG. 7.

We claim:

The ornamental design for a telescopic crane boom, substantially as shown.
